UNITED STATES PATENT OFFICE

146,624

DESIGN FOR A COMBINATION VANITY AND RADIO OR SIMILAR ARTICLE

Joseph J. Swartzmiller, Carnegie, Pa.

Application February 21, 1946, Serial No. 126,819

Term of patent 3½ years

(Cl. D33—6)

To all whom it may concern:

Be it known that I, Joseph J. Swartzmiller, a citizen of the United States, residing in Carnegie, in the county of Allegheny and State of Pennsylvania, have invented a new, original, and ornamental Design for Combination Vanity and Radio or Similar Article, of which the following is a specification, reference being had to the accompanying drawing, forming part thereof.

Figure 1 is a perspective view of a combination vanity and radio or similar article showing my new invention; and

I claim:

The ornamental design for a combination vanity and radio or similar article, as shown.

JOSEPH J. SWARTZMILLER.
